DIVERTER INFORMED ADAPTIVE WELL COMPLETION SYSTEM

RELATED APPLICATIONS

This application relates to U.S. Pat. No. 9,903,178, issued Feb. 27, 2018, entitled "HYDRAULIC FRACTURING WITH STRONG, LIGHTWEIGHT, LOW PROFILE DIVERTERS," which is hereby incorporated fully herein.

This application claims priority to U.S. patent application Ser. No. 16/885,125, filed May 27, 2020, entitled "Improved Fracking Apparatus and Methodology," which claims priority to (and is a division of) U.S. patent application Ser. No. 16/576,745, filed Sep. 19, 2019, and issued as U.S. Pat. No. 10,822,914, all of which are hereby incorporated fully herein by reference.

BACKGROUND

The example embodiments relate to oil and gas fracturing and production.

Oil and gas production have used a process called hydraulic fracturing ("fracing") since the late 1940s, where the fracturing process is used to further fracture deep underground rock formations so as to enhance the release of oil and/or gas. In further detail, fracturing is preceded by first drilling a vertical well to a depth that can be one to two miles or more, and once the vertical well reaches a certain depth, then extending the well horizontally, which extension can be an additional mile or more. The well is then encased with steel pipe cemented in the hole. Thereafter, and typically in repeated stages, corresponding to respective segments of length along the well, a number of perforations are formed along a segment of the steel pipe. Next, a high pressure, high flow rate fluid is introduced into the well, the fluid comprising overwhelmingly water, and the fluid also may include proppant (normally sand and/or ceramic) particles and a relatively small amount (e.g., less than two percent) of one or more additives/chemicals. The high pressure frac fluid passes through the already-formed perforations in a particular well segment and into the rock formation adjacent and proximate the perforations. Once a stage is fracked, it is isolated typically by a drillable plug, and then the process repeats for a next stage, until multiple (or all) stages likewise have been fracked.

In more detail, once the fracturing mixture exits the well casing and enters the adjacent formation, its pressure will further fracture the natural fractures of the rock formations it reaches. Thus, the fracturing materials and process thereby stimulate or improve production, for example from low permeability rock formations containing oil or gas, by creating or enlarging fractures within the formations. Moreover, in instances when the frac fluid includes sand or other particles, those particles will not only assist in applying pressure to and expanding the rock fractures, but once the fluid pressure is reduced or eliminated, those materials may remain in place, thereby maintaining or "propping" those expanded structures in place; accordingly, such materials are sometimes referred to as proppants. Thus, fracturing extends fractures already present in the formation, and causes new fractures, resulting in a network of fractures that substantially increases the permeability of the formation near the wellbore, and proppants can maintain the network of fractures for a period of time to enhance subsequent oil/gas production, once the fracturing process is completed. Also of note, as an alternative to proppants, the frac fluid may include acid, in which case the acid creates the fractures in

the formation and etches or dissolves the fracture faces unevenly, thereby forming dissimilar fracture faces that can only partially close leaving fractures through which oil or gas can flow more freely.

Common examples of proppants include silica sand, resin-coated sand, and ceramic beads (and possibly mixtures of them). Because silica sand is the predominant proppant used for fracturing, "sand" has become petroleum industry jargon for any type of proppant or combination of proppants used in fracturing. Therefore, the term "sand" in this document refers to any type of propping agent, or combinations of them, suitable for holding open fractures formed within a formation by a fracturing operation unless otherwise plainly stated. The term "frac fluid" will be used to refer to any type of hydraulic fluid used for fracturing that may be used to form fractures and/or enlarge natural fractures in the formation. Fracture fluids may be water-based, oil-based, acid or acid-based, and/or foam fluids. Additives also can be used to control desired characteristics, such as viscosity. Further, references to "frac fluid and sand" in the context of fracturing are intended to also include frac fluid and acid unless the context states or plainly indicates otherwise.

Because of differences in permeability of the rock adjacent (and exterior from the well relative to) each of the perforations due to different porosities or existing fractures (both naturally occurring and caused by perforating the casing), the rate at which frac fluid flows through perforations distributed along a wellbore may, and almost always does, vary along the length of the wellbore. When stimulating vertical wellbores over 60 years ago the petroleum industry frequently used a high number of perforations (up to 4 perforations per foot of casing) throughout most of the oil and gas pay zones of a wellbore. Such a large number of perforations resulted in the frac fluid and sand flowing first into more permeable rock. This resulted in fractures in the more permeable rock formations being packed with too much of the sand (or acid), which was intended to be distributed approximately equally through the perforations and into adjacent formations. The less permeable formations were, consequently, not being sufficiently fractured. As a result of this variance, a prior art approach was to introduce so-called diverters into the wellbore at certain points during the fracturing process, where the diverters would tend to seal the paths of least resistance, thereby diverting the frac fluid to other perforations and, hence, causing frac in rock formation areas of higher resistance. Historically, such diverters were solid, hard rubber balls, sometimes referred to as "ball sealers." More particularly, after pumping a portion of the frac fluid with sand or acid, multiple ball sealers were pumped into the well and carried by the frac fluid to the perforation being stimulated. The balls temporarily sealed some of the perforations—those adjacent to fractures formed in the more permeable rock—and diverted the frac fluid, with the sand or acid, away from the stimulated perforations to other perforations in the next most permeable zone of rock that had not yet been similarly or equally stimulated. After pumping of frac fluid ceases, the ball sealers, no longer being held against the perforations by the differential pressure between the frac fluid within the wellbore and the formation, fall off of the perforations to allow hydrocarbons from the fractured formation to flow into the well. However, the need for the relatively large and heavy ball sealers in vertical wellbores was minimized when industry began to selectively perforate only the better permeable zones (commonly referred to as "limited entry," which also typically involves completing a stage when a certain flow rate is met,

without necessarily knowing if that flow rate guarantees that certain perforations of the stage have been adequately fracked).

For horizontal or highly deviated directional oil and gas wells, the conventional petroleum industry practice today is to frac lateral wellbores in stages. Typically a large number of stages are employed to frac a lateral wellbore extending 4,000 to 7,500 feet or more, where the number can be in the hundreds. Each frac stage may have 4 to 8 clusters of perforations, with each cluster typically having 6 perforations. The purpose of frac in multiple stages is to distribute a generally equal amount of frac fluid and sand to all perforations in a manner that achieves optimal stimulation of each perforation along the entire length of the lateral portion of the wellbore, thereby creating extensive cracking/fracturing of the rock formation surrounding the casing along its entire length. Each frac stage is isolated from the other stages and perforated and fracked separately. The petroleum industry experience of fracturing a huge number of horizontal wells drilled to date appears to indicate that a large number of stages are required to ensure that a reasonably equal and sufficient volume of frac fluid and sand are pumped into each perforation. In the past few years, developments in hydraulic fracture technology indicate that superior stimulation results are achieved by using larger volumes of frac fluid and sand (15 million gallons and 15 million pounds of sand and more) pumped at extremely high rates (80 to 100 barrels per minute) and pressures (8,000-9,000 psi and more). The velocity of the frac fluid through the wellbore may reach or exceed 90 feet per second. Therefore, the industry continues to use the high-cost, multiple fracturing stages in an effort to distribute generally equal amounts of frac fluid and sand to all perforations in the horizontal (lateral) casing.

The commercial value of drilling horizontal wells with longer laterals and multiple stages fracked with larger volumes of frac fluid and sand pumped at high velocity and pressure has been established by achieving robust wells that have higher oil and gas producing rates and estimated ultimate recoveries of oil and gas. Effective frac stimulation of most or perhaps all of the perforations in a horizontal casing creates an extensive fracture system that opens and connects more reservoir rock to the wellbore. However, such frac jobs with a large number of stages are time consuming and expensive due to the repetitive plug, perforate, and frac operation required to isolate and frac each individual stage. Completion costs typically represent about one-half of the total drilling and completion costs of a horizontal well. Although it is tempting to reduce costs by reducing the number of frac stages and increasing the number of perforations to be stimulated per stage, fewer stages with more perforations per stage risks partial or unequal stimulation of the perforations within the stages. Wells with ineffective stimulation have lower initial production rates and lower ultimate recovery of oil and gas. Such costs are overlaid with other factors in attracting interest and funding into new wells, where such factors may be local, regional, or even worldwide, and include competitive production, political and regulatory policies, and alternative investments and energy sources. Accordingly, attracting new development and investment is more easily achieved with technologies that reduce costs while either maintaining or improving production, as are achieved with example embodiments described below.

SUMMARY

In one embodiment, there is a method of oil or gas production. The method forms: (i) a wellbore in a rock

formation, the wellbore including a lateral portion; (ii) introduces a plurality of perforation diverters into the wellbore, wherein each perforation diverter in the plurality of diverters includes circuitry for determining a pressure proximate the perforation diverter; and (iii) with each diverter in the plurality of perforation diverters, measures a respective pressure proximate the perforation diverter and within the lateral portion.

Other aspects are described and claimed.

BRIEF DESCRIPTION OF THE DRAWINGS

FIG. 1 is a simplified, schematic illustration of a well site with a wellbore within a formation undergoing hydraulic fracturing.

FIG. 2A is a representation of a prior art ball sealer.

FIG. 2B is a representation of a first embodiment of a low profile diverter in cross-section.

FIG. 2C is a representation of a second embodiment of a low profile diverter in cross-section.

FIG. 2D is a representation of a third embodiment of a low profile diverter in cross-section.

FIG. 2E is a representation of a fourth embodiment of a low profile diverter in cross-section.

FIG. 2F is a representation of a fifth embodiment of a low profile diverter in cross-section.

FIG. 3 represents a short section of a representative non-perforated cased horizontal wellbore upstream of the perforated representative wellbore shown in FIG. 4.

FIG. 4 illustrates the small section of a representative wellbore downstream of the representative wellbore shown in FIG. 3, with perforations formed therein and frac fluid flowing through the wellbore and perforations into the adjacent formation to cause fracturing.

FIG. 5 illustrates the small section of a representative wellbore of FIG. 4, with the introduction of low profile diverters into the flow of frac fluid within the wellbore, before they seal perforations temporarily.

FIG. 6 illustrates the small section of a representative wellbore of FIG. 5, with the diverters previously introduced into the flow of frac fluid sealing perforations adjacent to stimulated formations.

FIG. 7A illustrates a plurality of diverters shown flowing through the interior of a horizontal wellbore casing, including smart diverters having associated processing functionality.

FIG. 7B illustrates an alternative smart diverter.

FIG. 8 illustrates an electrical/functional block diagram of an example embodiment implementation of the smart diverter core 704SDC from FIG. 7.

FIG. 9 illustrates a downhole smart diverter interrogation system 900.

FIG. 10 illustrates an example embodiment of the FIG. 1 equipment 105, in addition to other apparatus that may communicate with the equipment 105.

FIG. 11 illustrates a flowchart of an example oil and gas fracturing and diverter method 1100, as may be implemented at the FIG. 1 well site 100.

FIGS. 12A and 12B illustrate a pulsing fracturing system 1200.

FIGS. 13A and 13B illustrate an alternative pulsing fracturing system 120.

FIG. 14 illustrates a portion of another alternative pulsing fracturing system 1400.

DETAILED DESCRIPTION OF EXEMPLARY EMBODIMENTS

The following description, in conjunction with the appended drawings, describe one or more representative

example embodiments. Unless otherwise indicated, they are intended to be non-limiting examples for illustrating the principles and concepts of claimed subject matter. Like numbers refer to like elements in the drawings and the description.

FIG. 1 is a schematic illustration of a representative example of a wellbore undergoing fracturing. It is not to scale. In this implementation a well site 100 has a well head 102 disposed at a top of a wellbore 106. The well head 102 includes one or more couplings (e.g., via a manifold or the like) to a source of frac fluid 104. The source 104 may be comprised of one or more tanks, pulsing apparatus, reservoirs, or other storage structures for fluid and sand or acid. The well head 102 may include, or have coupled with it, various equipment 105 to include sensors, including or separately a surface pressure sensor 103, and with various computational and/or transceiver functions as detailed later in connection with evaluating pressure and other conditions in, and associated with, the wellbore 106, as well as for directing fracturing operations in response to those conditions. The equipment 105 also may communicate with the well head 102 or other associated apparatus in connection with providing control relating to the flow, including pulsing, from the source 104 and, as detailed later the introduction of diverters into the wellbore 106. Further, the surface pressure sensor 103 may be arranged to measure fluid pressure at the well head 102. Fracture fluid stored in the storage 104 may be mixed with a sand (or other particles, such as ceramic) or acid. Alternatively, sand or acid is introduced to the fluid at or upstream of the well head 102. In some implementations, for example when the target subterranean formation is a carbonate formation, the fracture fluid may contain acid, in which case proppants may be unnecessary as the acid eats away the formation so that it cannot close. The well head 102 controls the injection of fracture fluid into the wellbore 106. The wellbore 106 may be horizontal (also referred to as lateral), deviated, or vertical. In the example of FIG. 1, the wellbore 106 extends horizontally into a target subterranean formation 110. The wellbore 106 is cased using a steel pipe 108 that is cemented in place. However, in some applications, the casing may not be cemented. Also, a casing liner may be used for the lateral section of the wellbore 106.

Perforations 112 are formed through the well casing 108 to expose the surrounding subterranean formation 110 to the interior of the wellbore 106, thereby allowing pressurized fracture fluid with sand or acid to be injected through the perforations into the subterranean formation. The well casing 108 may be perforated using any known method that produces perforations of a relatively consistent and predictable size. For example, the perforations 112 may be formed by lowering shaped blasting charges into the well to a known depth, thereby creating clusters of perforations at desired points along the wellbore 106. In a typical application, the perforations will, for example, be 0.4 to 0.5 inches in diameter, but in other applications they may have smaller or larger diameters.

During fracturing operations, fracture fluid will be pumped through the well head 102 and into the wellbore 106. The fluid will flow toward the perforations 112, as indicated by flow lines 114, and then out of the perforations 112 and into formation 110 to create new or enlarged fractures 116 within the formation. In this demonstrative, schematic illustration of FIG. 1, the fractures 116 of the formation 110 are indicated next to only some of the perforations 112, but not all. This limited creation of the fractures 116 in this example is occurring, for example, in only certain portions or areas of the formation 110 into which more fracture fluid is flowing due

to, for example, higher permeability in the areas where such fractures are shown, relative to the formation adjacent to the remaining perforations, which are indicated in the figure as having no new or enlarged fracturing, though in practice, new fractures or enlargement of existing fractures may in fact be taking place to a smaller degree. In other words, the fracturing is not necessarily equally effective (in terms of successfully creating corresponding fractures 116), at the same time, through all of the perforations 112.

10 In some implementations, a downhole pressure sensor (or pressure sensor array, or plural sensors) 120 may be placed lowered into the horizontal portion of wellbore 106 near the perforations 112 to measure the pressure of the fracture fluid close to perforations 112. Indeed, as detailed below, in certain example embodiments, pressure sensing is achieved downhole by associating pressure sensing apparatus with selected diverters.

15 Although, in this example, the wellbore 106 is not divided into multiple fracture stages, the wellbore 106 within the formation to be fractured can be divided into fracture stages, with each stage separately isolated and fractured. For example, and while not shown, FIG. 1 could be illustrative of a first area (or stage) which, after some amount of fracturing, is sealed off with a plug, then defining a new area, which in FIG. 1 would be to the left of the plug, that is not yet perforated or fractured. The above process can then be repeated, with respect to that new stage/area. The example embodiments, however, seek to significantly reduce the number of such areas for which a corresponding perforate, fracture, and plug must be repeated, 20 which in turn can substantially reduce the overall cost of well completion. More particularly, the diverters, fracturing (including pulsing), and diverter-provided information, are combined in a completion-adaptive system that operates in response to such information, as may evolve during the completion steps or from prior analyses, including prior well-completion databases and the like, so as to adjust well completion apparatus and steps, including reducing the number of well stages, to improve well completion efficiency. Accordingly, the diverters, as well as information 25 processing from such diverters, allow for a reduction in the number of stages that is otherwise required to achieve similar results. They also can be used to fracture without stages the entire wellbore within the zones of the formation expected to produce oil or gas.

30 FIG. 2A illustrates, for purposes of comparison, a conventional, solid ball sealer 200 of the type found in the prior art. It has uniform diameter. Its width "W" is equal to its height "T," which is equal to its diameter. The diverters 202, 204, 206, 208 and 210 of FIGS. 2B-2F illustrate different 35 cross-sectional shapes of a diverter that is relatively thin and lightweight (as compared to ball sealers), strong, and has a lower profile as compared to the prior art spherical diverter. The low profile diverters are sized to extend in one dimension longer than the largest portion of a perforation, so the 40 diverter extends over and temporarily seals a stimulated perforation, thereby diverting the flow of the fracture fluids and proppants to non-stimulated perforations. Each such low profile diverter has, in an example embodiment, an impermeable body with dimensions measured along each of two 45 axes (the x and z axes in the coordinate frame illustrated in the figures), large enough to cover and temporarily seal a perforation in a well casing of a size that is typically made or that might be made for the particular application. In these examples each has the same width W, for example of an inch 50 (or slightly more or less than an inch), in one or both of the x and z dimensions, which is the diameter of ball sealer 200 (FIG. 2A), so that when the width W is in both the x and z

dimensions, the diverter provides a circular outer circumference in the x-z plane. But, unlike a ball sealer, each diverter has a dimension along an axis orthogonal to the other two axes (the y-axis) that is a substantially smaller than dimensions of the diverter along the first two axes, resulting in a relatively thin cross-section (or profile) that reduces drag caused by fluid flowing past the diverter while it seals a perforation. Further, in each of the illustrated examples, along the portion of the diverter extending in the y-dimension, that is, between the outermost perimeter of the x-z plane, the surface is curved or smooth (no point or vertex), within the outermost boundary defined in the x-z plane. Due to the reduced drag, such a diverter is more capable of seating onto perforations and sealing them off without being unseated by continued fluid flow over or past the diverters. The shape of the outer circumference of diverters in a plan view, which would be along the y-axis, or the cross-sectional shape of the diverters when sectioned normal to the y-axis (i.e., in the x-z plane), is circular in the examples given. However, other shapes could be used as long as the shortest dimension of the diverter in the x and z dimensions is large enough to cover and temporarily seal the expected perforations. Non-limiting examples of such shapes are oval, squarer, and polygonal shapes. Other shapes are possible.

When introduced into a flow of frac fluid into a wellbore during fracturing, each diverter 202 to 210 is intended to temporarily seal one perforation after it has been stimulated with frac fluid and sand or acid. Also in this regard, in some example embodiments, note that the shape, configurations, and outer perimeters shown in FIGS. 2B through 2F may be temporarily augmented with an external and dissolvable material to approach an initial spherical outside shape, so that the temporary spherical outer shape confirms to the same apparatus used in the prior art for loading spherical diverters into the wellbore 106. Thus, the temporary outer spherical shape operates compatibly with a spherical loading/unloading diverter launching device (not shown), so that diverters can be loaded into the diverter launching device and launched into the wellbore 106 having the spherical external shape, and thereafter the outer dissolvable material dissolves as the diverter travels with the frac fluid in and through the wellbore 106, whereby the dissolvable material is thusly removed from the exterior shape/configuration of the diverter, returning its shape as depicted in one of FIGS. 2B through 2F.

Further with respect to the shapes in FIGS. 2B through 2F, the specific cross-sectional areas for these diverters will vary based on different design and manufacturing considerations, the illustrated cross-sections of diverters 202 to 210 have much lower cross-sectional areas—preferably, 75 to 95 percent less—than the ball sealer 200 (or a comparable ball sealer capable of sealing similarly sized perforations). They are, therefore, subject to substantially less drag force exerted by fast moving frac fluid than a traditional ball sealer. This large reduction in drag force allows the diverters to seat on and form a temporary seal of the stimulated perforations more easily and reliably. The relatively small cross-sectional area of such diverters thus minimizes the risk that the high velocity frac fluid flowing through the perforated liner could cause (1) failure of some diverters to seat on and seal stimulated perforations, or (2) diverters to be unseated from the stimulated perforations before completion of the frac job. The temporary seal is broken, and the diverters unseat, when the frac fluid pressure drops and the pressure differential across the diverter drops to the point that there is insufficient pressure to hold them against the perforations, thus allowing hydrocarbons to flow into the well from the formation.

Turning now to the specific examples of low profile diverters shown in FIGS. 2B-2F, the diverters are positioned to show their minimum cross-sectional width W along the x axis of the coordinate frame adjacent to each of the figures. 5 As previously mentioned, each is shown with the same width as ball sealer 200 for purposes of comparison. Diverter 202 of FIG. 2B is shaped generally as a discus having an overall or greatest thickness T (measured along the y axis). The greatest thickness of the diverter 202 is in 10 the center, and the thickness tapers towards side edges of the diverter. In comparison to the ball sealer 200, the discus shaped diverter 202 has the same minimum width W, but a considerably smaller thickness T₁. The cross-sectional area of diverter 202 is much less than the cross-sectional area of 15 the ball sealer 200, and has a resistance to the flow of frac fluid estimated to be 25% of the resistance of the ball sealer 200. Accordingly, the discus shaped diverter 202 is capable of sealing a perforation, while having a much smaller cross-sectional area, and therefore a greatly decreased resistance to flowing frac fluid.

Diverter 204 of FIG. 2C is shaped as an erythrocyte, which has its greatest thickness T₂ along its outer perimeter or edge, but has center region with having a smaller thickness T₃. The resistance to frac fluid flow of the erythrocyte-shaped diverter 204 is estimated to be about 20% of the 20 resistance of the ball sealer 200.

Diverter 206 of FIG. 2D is shaped like a saucer, having a convex bottom surface 214 with a first radius and a concave top surface 212 with a second radius different than the first 30 radius. In this embodiment, the radius of the concave top surface 212 is greater than the radius of the convex side 214 so that the sides converge and intersect at outer edge 216 of the diverter. The diverter 206 has an overall thickness T₄ measured vertically from a lowest point of the convex bottom surface 214 to edge 216. Depending on the thickness T₅ (the actual thickness of which may depend on the materials and expected pressures), is estimated to have 35 approximately 10% of the resistance of fluid as that of the ball sealer 200.

Diverter 208 of FIG. 2E is shaped as a disk, with a generally consistent thickness T₆ across its width W. In example shown, its resistance to the flow of frac fluid is estimated to be about 8% of that of the ball sealer 200. If the thickness is decreased to T₇, as shown by the example 45 diverter 210 in FIG. 2F, its estimated resistance to the flow of frac fluid drops to about 25% of that of the ball sealer 200.

The actual cross-sectional area of these diverters 202, 204, 206, 208, and 210 may vary from each other, even if intended to seal the same sized perforations. The exemplary diverters of FIGS. 2B-2F have flat to curved surfaces to facilitate forming a temporary seal of the perforations. Furthermore, a diverter is constructed to be strong enough to seal the perforation without failing under the differential pressure across the diverter (the pressure acting against the 50 surface of the diverter facing the inside of the casing less the pressure acting against the surface of the diverter facing the perforation) to which it is expected to be subject when seated on a perforation. The differential pressure will be the difference between the pressure of the frac fluid on the diverter 55 inside the casing, acting against the diverter when sealing a perforation, which is a function of the pumping pressure on the frac fluid and the hydrostatic pressure of the frac fluid within the casing, and any fluid pressure outside the casing. In one embodiment, each of the diverters 202 to 210 is 60 capable of withstanding at least 5000 psi of differential pressure without failing. In another embodiment, each diverter can withstand a differential pressure of at least 7500 65

psi without failing. In yet another embodiment, each diverter can withstand a differential pressure of at least 10,000 psi without failing. Furthermore, a diverter may, optionally, have a flexible and durable surface or coating to enhance sealing of the perforations. The diverters 202 to 210 may be partly or entirely constructed out of material or materials that allow them to be flexible, further enhancing their ability to form a seal over perforations 112. In some embodiments, diverters 202 to 210 may be constructed out of a composite material, which can be stronger and lighter than steel.

The shapes of diverters 202 to 210, particularly diverters 202, 204 and 206, allow them to be hollow to increase their displacement without increasing their weight. Therefore, the diverters may have a weight that is heavier, lighter or equal to the weight of its displacement of frac fluid. The embodiments of diverters 202, 204 and 206 are shown in figures as being hollow or at least having a partially unfilled cavity. However, in alternative embodiments, these diverters could be made solid or can include other apparatus embedded within the outer walls of the diverter, as detailed later starting with FIG. 7. The disk and wafer shaped diverters will be strong and lightweight without necessarily being hollow, but again may include internal apparatus as detailed later.

Referring briefly back to FIG. 1, frac fluid is shown being pumped downhole from the well head 102 and into the wellbore 106, as indicated by the arrows within the wellbore 106. At this point, pumping has continued long enough to begin to fracture parts of the formation 110. The frac fluid is shown flowing into perforations 112 associated with relatively larger fractures 116, indicating that those parts of the formation have been stimulated. The large fractures 116 are in zones or areas of the formation with relatively high permeability. A less developed fracture 118 is intended to illustrate an area of less permeability that has not yet completed fracturing. The other perforations have little to no fracturing of the formation next to them, that is, in the area of the formation that fluidly communicates with the opening of a corresponding perforation 112. Those areas of the formation have lower permeability and are not receiving enough frac fluid to start to fracture because it is flowing mostly into the parts of the formation with higher permeability.

Once some of the most permeable areas of the formation are approaching full stimulation, a predetermined number of thin or low profile diverters, such as any one or more of the types shown in FIGS. 2B-2F, are introduced at or near the well head into the flow of frac fluid entering the wellbore, without stopping pumping of frac fluid and sand. These diverters are intended to temporarily seal only those perforations next to areas within the formation that have been fully stimulated—those, for example, next to fractures 116—and thus divert frac fluid and sand to less fractured or yet-to-be fractured areas of the formation.

Referring now to FIGS. 3 to 6, FIG. 3 illustrates a small section 300 of a horizontal wellbore casing without perforations, and that is upstream of another section 300 of casing with perforations, for example with the latter shown in FIG. 4. In FIG. 3, flow arrows 302 indicate the direction of fluid flow downhole. The flow arrows 302 indicate how fluid flows in unperforated casing before reaching the FIG. 4 perforated casing 300. FIG. 4 shows multiple perforations 402, after frac fluid has begun to be pumped under high pressures and at high flow rates downhole and through the wellbore. The flow of frac fluid is indicated by flow lines 404. All of the perforations 402 are not sealed and therefore open. The pressurized frac fluid flows into the perforations

402 adjacent to the areas or zones of a subterranean formation 406 where it is most permeable, as shown by directional lines 404. In the figure the perforations 402 are adjacent to rock having, essentially, the same amount of permeability 5 adjacent each of the respective perforations 402. Thus, in this example, frac fluid is shown flowing into all of the perforations and creating roughly the same amount of fluid into corresponding fractures 408. Although not shown, frac fluid, and thus also sand or acid, is not flowing, or flowing 10 at lower rates, into perforations elsewhere within the segment of the wellbore 106 that is being fracked (a segment corresponds to one frac stage or length of wellbore undergoing a fracing operation) that are adjacent to less permeable parts of the formation. Thus, the FIG. 4 fractures 406 are 15 being fractured first, while less permeable rock formation adjacent other open perforations are not being fracked, or are fracked to a lesser extent than those shown in FIG. 4. Once the formation adjacent to perforations 402 are fully stimulated, meaning the frac fluid has fractured the subterranean formation 406 and the fractures 408 are packed with sand to hold them open, then as also shown below in additional figures, a predetermined number of low profile diverters, such as those shown in FIGS. 2B-2F, are pumped into the 20 flowing frac fluid stream to seat and temporarily seal perforations 402 and thereby the frac fluid is redirected or diverted to the perforations within the wellbore adjacent to less permeable areas of formation to create fractures 118.

In FIG. 5 the low profile diverters 500, which in this 30 example are discus shaped but can be any of any low profile shape capable of sealing against the perforations, are shown entrained in the flow of frac fluid and being moved toward perforations 402 by the flow of the frac fluid and sand into the perforations. In FIG. 6, the low profile diverters 500 are 35 shown seated on the openings of the perforations 402, engaging the edges of the perforations and thus temporarily sealing the perforations against substantial frac fluid flow. (A small amount of leakage may occur even when sealed). The high pressure of the frac fluid within the wellbore pushes 40 against the seated diverters 500 with sufficient force to keep them in place while the frac fluid flows past them, as indicated by the frac fluid flow lines 404 in the figure. Because of the low profile of the diverters, the frac fluid moving at a high rate within the wellbore is less likely to dislodge the low profile diverters as compared to conventional ball sealers.

Each diverter should temporarily seal one perforation 402, and only a perforation 402 that has likely been stimulated with frac fluid and sand or acid, assuming that the diverter is introduced into the frac fluid flow at the right time. The number of diverters 500 that are introduced into the flow of frac fluid is less than the number of perforations 402 being stimulated. The pumping of the frac fluid continues and, after a period of time, an additional selected number 55 of additional diverters 500 can be introduced into the flowing frac fluid stream to temporarily seal some, but not all, of the remaining perforations. This process of continuing to pump frac fluid for some period of time before introducing a selected number of additional diverters 500 is informed 60 by information from the diverters as detailed below, and can be selectively repeated from such information one or more times, as is necessary to selectively and progressively frac less permeable parts of the formation, until all of the volume of frac fluid with sand and the number of diverters designed 65 and purchased for the job have been essentially depleted by pumping indicating that the stimulation of all perforations have been reasonably completely.

Use of low profile diverters 500 as described above allows for the number of frac stages to be reduced, and possibly eliminate the need for frac stages, even for wells with relatively long wellbores, even for long laterals that require fracturing at very high rates and pressures, as compared to current methods that do not make use of low profile diverters.

FIG. 7A illustrates a plurality of diverters shown flowing through the interior of the section 300 of a horizontal wellbore casing, where by way of example the outer shape of the diverters are that of diverter 202 from FIG. 2B, and the width W may be an inch (or slightly more or less than an inch). Of the total diverters shown in FIG. 7A, in an example embodiment, the majority are indicated as diverters 702D, taking the same form as shown earlier. However, a minority (e.g., 1 in 10) of the diverters introduced into the interior of the section 300 are, in an example embodiment apparatus and methodology, enhanced to provide what will be referred to herein as a smart diverter, hence shown in FIG. 7A as a smart diverter 704SDSD. Alternatively, a majority, or even all, of the diverters may be provided as a smart diverter 704SD. Each smart diverter 704SD may have the shape of any of the diverters shown in FIGS. 2B through 2F, or also may include yet another embodiment that is spherical, akin to the prior art FIG. 2A, but that is novel from the prior art due to the inclusion of additional apparatus within, and/or use of, the diverter, as will be explained. In any event, as the diverters are introduced into the wellbore casing, such as through a manifold of well head 102, diverter distribution information may be obtained and maintained, including the number of total diverters introduced into the wellbore, the number of those that are smart diverters or have some other varying attribute (e.g., shape/profile), and the time of entry of each (or some) of the diverters. Each smart diverter 704SD has additional apparatus affixed to the diverter, and preferably within (i.e., encased or enveloped within) or attached to the outer walls of the diverter, providing various additional functionality to the diverter beyond the ability to fill a perforation in the wellbore interior. Thus, recalling that the earlier description indicated that example embodiment diverters have an interior that is hollow or filled, preferably a smart diverter core 704SDC is provided within the interior of selected ones of the diverters, either in the hollow space or encapsulated or otherwise positioned in the diverter interior, thereby providing the smart diverter 704SD. As detailed below, therefore, additional functionality may be provided by the smart diverter 704SD, either as it travels with the frac fluid and/or once the smart diverter 704SD is seated into a well casing perforation. Including smart diverter 704SD along with normal diverter 702D, in a same frac fluid stream, should result in the smart diverter core 704SDC capturing all frac data as incurred by the smart diverter 704SD.

FIG. 7B illustrates an alternative smart diverter 706SD, as may be used in lieu of or in addition to the smart diverters 704SD in FIG. 7A. Generally, a majority of the outer shape of the FIG. 7B smart diver 706SD is the same as that of the FIG. 7A smart diverter 704SD, that is, presenting a discus shape. Further, the smart diverter 706SD includes one or more smart diverter cores 706SDC. The smart diverter core 706SDC is located to extend, at least in part, beyond the outer majority of the volume of the smart diverter 706SD, in contrast to being located within a central interior, as is the case for the FIG. 7A smart diverter 704SD. In the FIG. 7B example, the smart diverter 706SD includes two smart diverter cores 706SDC, each located at a geometrically opposing (180 degrees apart) edge of the smart diverter

706SD. Each of the smart diverter cores 706SDC may be affixed, or caged, in this position by fitment (e.g., molding, adhesive, retractable, detachable, snap on/off fit, etc.) to a respective receiving region 708. Each smart diverter core 706SDC may include the same apparatus and provide a same functionality as the FIG. 7A smart diverter core 704SDC, for example as detailed in FIG. 8. The alternative FIG. 7B fitment, however, of the core 706SDC to the remaining body of the smart diver 706SD can provide various benefits. For example, each core 706SDC is more readily physically accessible, for example allowing a different timing of assembly of the core 706SDC to the rest of the smart diverter 706SD, where for instance a shorter battery life (or charge) may be required between the time the smart diverter 706SD is fully constructed and introduced into a well. As another example, without constraining the core 706SDC to the interior of the smart diverter 706SD, there may be larger volume to include, or at least accommodate different sized or larger cores. As still another example, each core 706SDC may be more readily replaced, repaired, substituted, re-used, or even modified or improved, as needs present, while then being physically fit to the remainder of the device. Lastly, note that all of the FIG. 7A and FIG. 7B diverters, smart or otherwise, as well as the diverters of FIGS. 2C through 2F, may be manufactured to be slightly heavier than the frac fluid the diverter displaces. The slick water frac fluid used in most modern frac jobs has about the same specific gravity as potable city water, so the resultant slightly heavier diverter is referred to herein as a balanced diverter(s). Such balanced diverters are carried to perforations yet to be fully stimulated and held in place by the flowing frac fluid. Such "balance" assures that the diverter will accomplish the function for which it was designed.

FIG. 8 illustrates an electrical/functional block diagram of an example embodiment implementation of the smart diverter core 704SDC from FIG. 7A (or of the smart diverter core 706SDC from FIG. 7B). The core 704SDC is in part a computational device, and it is noted in this regard that contemporary technology now has offerings of computation cores and ancillary items with a form factor as small as one millimeter cubed. For example, so-called smart dust technology proposes millimeter-scale self-contained microelectromechanical devices that include sensors, computational ability, bi-directional wireless communications technology, a power supply, and the ability to self-organize into ad hoc networks, and currently advertised is a Michigan micro-mote that proposes such a device. Toward this end, therefore, the blocks of FIG. 8 illustrate example embodiment functionality to be implemented in such a device and in connection with the smart diverter core 704SDC. With these blocks, as further detailed below, as a diverter enters and then travels inside the wellbore 106, and also once the diverter later exists the well, data may be captured and stored/communicated, so as to further enhance the fracturing methodology, including but not limited to reducing the number of necessary fracturing stages, thereby drastically reducing cost and time to production.

Looking in more detail to FIG. 8, the core 704SDC has an internal power supply 705 (e.g., lithium or other battery) and also includes a central processing unit (CPU) 710, coupled to a system bus BUS. Also coupled to the system bus BUS is an input/output (I/O) interface 712, which may communicate with peripheral I/O functions outside of the core. Preferably, with the core 704SDC internal to the diverter, then I/O is with other devices also internal to the diverter, although such additional devices are not shown. Such

devices are contemplated, however, and could replace or augment those shown in FIG. 8. Additionally, also contemplated is that prior to the diverter being introduced into the wellbore 106, the I/O could physically be through the diverter body. The CPU 710 refers to the data processing capability of the core 704SDC, and as such may be implemented by one or more CPU cores, co-processing circuitry, and the like. The particular construction and capability of the CPU 710 is selected according to application needs, such needs including, at a minimum, the carrying out of the functions described in this document, and also including such other functions as may be desired. The core 704SDC also includes a system memory 714 coupled to the system bus BUS, and the system memory 714 provides memory resources of the desired type useful as data memory for storing input data and the results of processing executed by the CPU 710, as well as program memory for storing the computer instructions to be executed by the CPU 710 in carrying out those functions. Of course, this memory arrangement is only an example, it being understood that the system memory 714 can implement such data memory and program memory in separate physical memory resources, or distributed in whole or in part outside of the core 704SDC.

The core 704SDC also includes a wireless interface 716 that is conventional in nature of an interface or adapter by way of which the core 704SDC may communicate with other wireless devices, such as in a local sense or a more extensive network, with an example provided below in connection with FIG. 8. Thus, the wireless interface 716 may include various types of radio communication apparatus, including WiFi, Bluetooth, and other known or ascertainable communication protocols and standards. In this regard, also in an example embodiment, apparatus (described later) are contemplated to poll or otherwise communicate with each smart diverter 704SD, including any of when it enters, as it travels within the wellbore 106, and/or once it is seated in a perforation or after it is retrieved from the wellbore 106. Such apparatus may be independent of the wellbore 106, for example by positioning a sonde, transceiver, or the like down and through the wellbore 106 so that as the sonde is proximate, or within some communication range of a smart diverter 704SD, either unidirectional or bidirectional communications are facilitated between the two, an example of which is detailed later. Such a sonde, for example, may be controlled and/or in communication with the equipment 105, where the steering and positioning of the sonde, including its depth along the wellbore 106, may be controlled and/or evaluated. In this manner, in addition to position sensing by a smart diverter 704SD, the sonde and/or equipment 105 may further detect a location (or approximate location) of a diverter once it is secured in a perforation, thereby further being able to communicate pressure and other information associated with that determined position.

In addition, also contemplated in certain embodiments is using a portion of the wellbore 106 as part of the communication path; for example, as earlier mentioned, part of the casing may be steel, in which case electromagnetic waves may be made to use the steel to communicate with diverters using the steel, or possibly other structures, as a waveguide in communicating signals from a smart diverter 704SD to other locations within the wellbore 106, or even along the wellbore 106, either directly or via intermediately-positioned other smart diverters 704SD, to the top and out of the well. In another example, markers or materials (e.g., magnetic, RFID) may be included in selected locations of the casing, for example in joints (or collars) between casing pieces (e.g., Teflon or plastic rings placed in the collar), or

as part of a material located there such as a doping, that may communicate with, or be detected by, the smart diverter as it travels past such a location or multiple locations. For example, in one example embodiment, such a material is included in each of a number of evenly spaced joints. Then, once the smart diverter 704SD is introduced into the well, a part of the smart diverter 704SD (e.g., the wireless interface 716) detects each such joint as the smart diverter 704SD passes that joint, and the smart diverter 704SD likewise keeps a count (e.g., in the CPU 710 or the system memory 714) of each passed/detected joint. Such information may provide a depth or length position indication of the smart diverter 704 SD, and potentially its relative circumferential position as well. Accordingly, the smart diverter 704SD can store this data and transmit it, or the smart diverter itself (again, using the CPU 710) can calculate the distance traveled by the smart diverter 704 SD (and correspondingly, the depth in the well), as the product of the distance between each detected joint times the number of joints the diverter has passed, or that product can be added to some additional offset, for example as may be a distance from the top of the well to the first joint that includes such a material.

In all events, the wireless interface 716 provides remote access between the smart diverter 704SD and other (e.g., network) resources, which can include other computational devices such as associated with equipment 105 at or above the surface, below which the well is formed. In this manner, an operator may query or collect data from one or more smart diverters 704SD, whereupon the operator, either directly or with the use of additional software of the like, can interpret data taken and communicated by, one or more diverters, so as to modify the fracturing process, particularly, for example, with respect to reducing the number of fracturing stages.

Further in an example embodiment, the smart diverter core 704SDC includes a (or more than one) pressure transducer(s) 718 or comparable device for detecting pressure changes, including measuring acoustics and acoustical changes, and possible correlations between acoustics and pressure changes. As shown, the pressure transducer 718 is integral to the core 704SDC, but alternatively such a transducer may be a separate apparatus (e.g., communicating via the I/O 712), again internal to the diverter, but otherwise in communication with the processing and memory functionalities of the core 704SDC. In this regard, the pressure transducer(s) 718 is preferably configured and controlled to capture and store and/or communicate one or two pressures, namely: (i) dynamic pressure, that is, the increase in a moving fluid's pressure over its static value due to motion; and (ii) differential pressure once the diverter 704SD is situated in a perforation, which pressure as defined earlier is the pressure between the frac fluid within the wellbore and the formation—in this regard, also contemplated is that the pressure transducer(s) 718 may include some manner of directionality, for example, relative to the shape of the transducer so as to measure pressure on one side of the transducer (e.g., facing the fluid interior of the wellbore) versus the other side of the transducer (e.g., facing the rock formation external from the wellbore). Additionally, detected changes in pressure may be correlated to known or suspected events near the detecting sensor(s), such events including an initial breakdown of the rock proximate a frac stage as well as ongoing above-threshold pressure changes that can indicate advancement of the rock formation breakdown as it accepts more and more fluid/proppant and pressure changes as diverters seat in respective perforations.

Lastly, the smart diverter core 704SDC may include a position detection block 720. The position detection block 720 is intended to include functionality to assist with the diverter 704SD communicating its position either as it travels within and/or once it seats in a perforation within the wellbore 106. For example, the position detection block 720 may include some form of global positioning system (“GPS”) functionality, although it is recognized that the ability to directly communicate with the GPS system would be limited at the underground depths of a wellbore. Thus, the block 720 may include the ability to capture position at the surface point of entry into the wellbore 106, with additional dead reckoning features (e.g., navigational speed and direction measures, including the above-mentioned joint markers) from which position can be further estimated as the diverter travels within the wellbore 106.

According to an example embodiment, by way of example, the system memory 714 provide a computer readable medium that stores computer instructions executable by the CPU 712 to carry out the functions described in this document. These computer instructions may be in the form of one or more executable programs, or in the form of source code or higher-level code from which one or more executable programs are derived, assembled, interpreted, or compiled. Any one of a number of computer languages or protocols may be used, depending on the manner in which the desired operations are to be carried out. For example, these computer instructions for creating the model according to example embodiments may be written in a conventional high level language, either as a conventional linear computer program or arranged for execution in an object-oriented manner, or in numerous other alternatives including those well-suited for web-based or web-inclusive applications. These instructions also may be embedded within a higher-level application. In any case, it is contemplated that those skilled in the art having reference to this description will be readily able to realize, without undue experimentation, the example embodiments in a suitable manner for the desired functionality. These executable computer programs for carrying out example embodiments may be installed as resident within the core 704SDC, or alternatively may be resident elsewhere and communicated to the core.

FIG. 9 illustrates a downhole smart diverter interrogation system 900. The system 900 includes coiled tubing 902, which is well-known in the art as a continuous length of small-diameter pipe (e.g., steel) and related surface equipment (not shown) for working on live, producing wells. The tubing 902 is commonly delivered near the well head, and from a reel on which the tubing is spooled. The tubing 902 is drawn from the wheel and fed down into a wellbore 106 (see FIG. 1), for example, for delivery of tools or retrieval of items in the wellbore 106. In the illustrated embodiment, however, an electrical cable 904 is located internally within the tubing 902 and communicates with an interrogation transceiver 906. The transceiver 906 includes adequate circuitry, capable of operating within the well environment, and implemented in a desirable level of hardware and software. Further, the transceiver 906 is for communicating with smart diverter cores 704SDC that have been displaced down the wellbore 106, as described above. For example, the transceiver 906 may communicate wirelessly to cores 704SDC, along one or more frequencies (e.g., channels) to communicate either singularly or with multiple cores 704SDC at a time, or quickly switching to communicate (e.g., frequency scanning, hopping, changing, or the like) so

as to communicate with different ones of the cores 704SDC, once those cores are either moving, or have affixed into a respective perforation.

In example embodiment, the transceiver 906 also includes or is coupled to apparatus for advancing the transceiver 906 to desirable positions within the tubing 902. For example, the end 902E of the tubing 902 may be displaced all the way down the wellbore 106, or to a known location within the wellbore 106. Thereafter, the transceiver 906 may be advanced to certain positions within the tubing 902, so that positional information is thereby known of the transceiver 906 (e.g., from the length of cable 904, the length of tube 902, dead reckoning technologies, and the like); accordingly, any cores 704SDC that may then communicate with the transceiver 906 also may be position-determined, relative to the known position information of the transceiver 906. For positioning the transceiver 906, in the illustrated example, one or more pressure-fitting bands 906BD are affixed to the outer perimeter of the transceiver 906, so that a seal is formed as between the outer portion of the bands 906BD and the inner diameter of the tubing 902. In this manner, as liquid is pumped downhole, that liquid may enter the interior of the tubing 902, and with the seal provided by the bands 906BD, the liquid pressure will advance the transceiver 906 downward through the interior of the tubing 902, thereby pumping the transceiver 906 to a desired stopping point in that interior. As examples, FIG. 9 illustrates potential positions A and B, such that the pumping pressure may be reduced when the transceiver 906 reaches either of those positions, in order to stop the transceiver 906 from further advancing along the interior of the tubing 902. Each potential position may correspond to a location within the wellbore 106 where the well casing has been perforated, with the expectation therefore being that diverters, including cores 704SDC, are likely to have sealed those perforations. Accordingly, with the transceiver 906 at position A or position B, nearby cores 704SDC may be interrogated, so as to record position and pressure data and other data consistent with the earlier description. Such data may be stored within the transceiver 906 and/or communicated (e.g., real time) via the cable 904 to data processing device at the far end of the cable, such as in equipment located atop the wellbore 106. Lastly, the transceiver 906 may be advanced back toward the top of the wellbore 106, either by pulling on the cable 904 (or, a separate physical cable parallel to cable 904, if the electrical connectivity of the cable 904 would not withstand the pulling force), or by retracting the tubing 902. Indeed, with the ability to retract the transceiver 906 in this manner, another contemplated alternative for positioning the transceiver 906, and thereby knowing that position, would be to advance the transceiver 906 to the tubing end 902E, and then retract the transceiver a retracted distance inside the tubing 902 a known distance, with the position thusly being the position of the tubing end 902E within the wellbore, minus the retracted distance.

FIG. 10 illustrates an example embodiment of the FIG. 1 equipment 105, in addition to other apparatus, some already described above, that may communicate with the equipment 105. The equipment 105 includes a computational system 1000. The computational system 1000 includes a central processing unit (CPU) 1002, coupled to a system bus BUS. Also coupled to system bus BUS is an input/output (I/O) interface 1004, which communicates with peripheral I/O functions by which a well operator may input or receive information provided to or from the computational system 1000, such as via a keyboard, display, a camera, microphone, speaker, buttons, touch screen, printer or printer

communications, and as one final example that is illustrated in FIG. 10, with the FIG. 9 smart diverter interrogation system 900, that is, signals and data to and from that system 900 also may be communicated with the computational system 1000. The CPU 1002 refers to the data processing capability of the computational system 1000, and as such may be implemented by one or more CPU cores, co-processing circuitry, and the like. The particular construction and capability of the computational system 1000 is selected according to the application needs of the system, such needs including, at a minimum, the carrying out of the functions described in this document, and also including such other functions as may be executed by the equipment 105, in connection with well completion and production. In the architecture of the computational system 1000 according to this example, a system memory 1006 is coupled to system bus BUS and provides computer readable medium memory resources of the desired type useful as data memory for storing input data and the results of processing executed by the CPU 1002, as well as program memory for storing the computer instructions to be executed by the CPU 1002 in carrying out those functions. Of course, this memory arrangement is only an example, it being understood that the system memory 1006 can implement such data memory and program memory in separate physical memory resources, or distributed in whole or in part outside of the computational system 1000.

The computational system 1000 also includes a network interface 1008 that is conventional in nature of an interface or adapter by way of which the computational system 1000 accesses network resources that are either on a network or that communicate to a network. In this context, the network interface 1008 is shown connected to a wide area network (WAN), such as the global Internet, and a smart diverter 704SD (or 706SD) is also shown connected, by a link LNK, to communicate with the WAN; for example, recall from FIG. 8 that the smart diverter 704SD includes its own wireless interface 716, so to the extent that interface 716 can communicate with the Internet (either directly or indirectly, including having its data read and then communicated to the Internet) or some other WAN, the FIG. 10 computational system 1000 can likewise communicate with the WAN, thereby providing bi-directional communications between the computational system 1000 and the smart diverter 704SD. In this manner, data obtained by the smart diverter 704SD, including when in the wellbore 106, can be communicated to the computational system 1000 of the equipment 105. To facilitate such communications, the network interface 1008 may include various types of communication apparatus, including cell communications, WiFi, Bluetooth, wired, and other known or ascertainable communication protocols and standards. In all events, the network interface 1008 provides the computational system 1000 access to network resources, which also can include an illustrated hosting computer 1010 which also may be accessible on a smaller (e.g., local area) network, or a wide-area network such as an intranet, a virtual private network, or over the Internet; hence, via those arrangements, various wired and wireless communications may be achieved. In this embodiment, the hosting computer 1010 is a computer system, of a conventional architecture, and as such includes one or more central processing units, system buses, and memory resources, network interface functions, and the like. According to an example embodiment, the hosting computer 1010 includes a program memory 1012, which is a computer-readable medium that stores executable computer program instructions, according to which the operations described in

this document are executed and so as to communicate information to, and receive information from, the computational system 1000. In an example embodiment, these computer program instructions may be executed in part or whole by either the hosting computer 1010, or the computational system 1000, so as to control well completion or production-related steps, and use of apparatus, based on information detected by one or more of the smart diverters 704SD. Further in this regard, a database 1014 is part of, or accessible by, the hosting computer 1010, so as to provide data relating to well completion or production-related steps and to data provided (and in some instances measured or detected) by one or more of the smart diverters 704SD, as further detailed below.

Given the preceding, the present inventive scope provides improved fracing apparatus and methodology. For instance, example embodiments improve apparatus in permitting extensive downhole pressure measurements that may be stored, and are communicated, for use, as an example, during fracing. Thus, an example embodiment method would facilitate determining breakdown pressure, which presently may be detected at the surface, but with an example embodiment may be more accurately determined by use of one more distributed pressure sensors in the wellbore. Moreover, with the pressure sensing associated with diverters, whether those diverters are spherical as in the prior art or non-spherical (e.g., in FIGS. 2B-2F), pressure is knowable in combination with the diverting functionality, and it is anticipated that more efficient manners of fracing may be conducted by having more precise, and more accurately position-fixed located (e.g., by GPS measure; by smart diverter communication; by coiled tubing; by sensing depth in the bore, for example with joint/collar marking and/or dead reckoning), measures of pressure and rapid pressure changes (e.g., pressure "spikes"), and temperature, as the fracing process is performed. For example, such pressure measures may be used to control fluid flow rate, fluid pressure, timing for entry of diverters, and determination of when a stage has been sufficiently fracked so as to complete that stage and start a next stage (or even potentially to reduce or eliminate staging altogether). Indeed, also contemplated is that the information provided by smart diverters, and transmitted back to the top of the wellbore 106, may be received and processed by computational equipment, for example as included in the FIG. 1 equipment 105. Accordingly, such information may be sufficient to reduce or eliminate certain human operations and decisions currently required in fracing stages, including for example the beginning and ending of frac stages, the admission of more diverters (smart or normal), and the control of pressures, flows, and other materials (e.g., proppants) flowed into the wellbore, thereby speeding the process and reducing possibilities of human error and resource needs.

FIG. 11 illustrates a flowchart of an example oil and gas fracing and diverter method 1100, as may be implemented at the FIG. 1 well site 100 and with apparatus described above, including the FIG. 10 equipment 105 in combination with smart diverters 704SD (or 706SD). The method 1100 is intended to be illustrative of certain methods using the described apparatus, but only by example so that other method steps may be added, removed, rearranged, and the like, so as to improve fracing by reducing the time to completion, for example by reducing the number of completion stages (and plugs), or alternatively stated by allowing longer length of lateral wellbore to be completed without dividing that length into one or more additional plugged stages.

The method **1100** starts with a step **1102**, which perforates a length of the lateral wellbore **106**, such as a stage. For example, the step **1102** may occur at the distal end of the wellbore **106**, that is, at the first stage, or at a later stage, for example if a plug or plugs have been located in the wellbore **106**, or after only a portion of the stage has been perforated. The perforation may be achieved, including the number of perforations formed, using manners known in the art. In some instances, the perforations may be considered in clusters, typically at different locations along the wellbore **106**, where some clusters may be expected to be in areas of the formation **110** having permeability (or porosity) that differs from other areas of the formation **110**, where generally the more permeable areas (and corresponding perforation cluster(s)) are expected to fracture under lower frac fluid pressures, as sometimes referred to as a primary cluster, while the less permeable areas (and corresponding perforation cluster(s)) are expected to fracture under higher frac fluid pressures, as sometimes referred to as a secondary (or even tertiary) cluster.

Next, a step **1104** introduces a first set of an integer number **S1** of diverters into the wellbore **106**, where one or more of the **S1** diverters is a smart diverter **704SD** (or **706SD**, as shown in FIG. 7B). The **S1** diverters may be introduced at the well head **102**, either manually, or through a partially or fully automated apparatus, and are carried downhole by the pumped fluid. The **S1** diverters, and particularly the smart diverters in that set, are introduced at least in part, or at least initially, for their pressure-detecting and reporting functionality, as the full diverting of perforations will occur in combination with additional diverters introduced later.

Next, a step **1106** detects as one or more of the **S1** diverters seats into a respective one of the perforations, where the detection occurs when there is a pressure change in the wellbore **106**. The step **1106** detection may occur by pressure detection at the well head **102** as is done in the prior art, but in an example embodiment, the step **1106** detection is either augmented with, or determined entirely from, pressure detected and transmitted from one or more of the downhole smart diverters **704SD**. Indeed, if each smart diverter **704SD** can be frequently or continuously monitored, then the smart diverter **704SD** will detect and transmit a rapid change in differential pressure at the instant it seats in a perforation, thereby confirming that seating action. Moreover, as explained earlier, each smart diverter **704SD** may be position tracked, so by knowing the position of a smart diverter **704SD** when it seats into a perforation, the location of the sealed perforation is thereby known. Moreover, in an example embodiment, each smart diverter **704SD** may be separately identified, for example by its position in the wellbore **106**, or by information provided by the smart diverter (e.g., a unique identifier, such as a multiple-bit code or serial number stored in the smart diverter, or a media access control (MAC) address, or some other option as may be ascertained by person of skill in the art.) Accordingly, when data is transferred from the smart diverter **704SD**, its identifier may be part of that data, and thereafter any additional pressures and events detected by the particular smart diverter **704SD** can be correlated to the same particular smart diverter **704SD**. In any event, step **1106** can identify when, and therefore how many of the step **1104** smart diverters over time, have seated. Additionally, note that step **1106** applies to all **S1** diverters, so in addition to detecting seating of each smart diverter **704SD** in the **S1** diverters, it also preferably identifies most or all seating of any normal diverter **702D** in the **S1** diverters, again using

either traditional manners or augmented or entirely based on information from nearby smart diverters **704SD** that also are in the wellbore **106**, for example as concurrently introduced in the step **1104**. Also in this regard, since the **S1** diverters are the first set of diverters introduced for the current stage, it may be desirable that a majority, if not all, of the **S1** diverters are smart diverters **704SD**, so as to facilitate more precise information at the outset, per diverter, as is available from each of those diverters because of the included smart technology. Alternatively, the pair of steps **1104** and **1106** may be repeated, first with smart diverters **704SD** (or a higher percentage of smart diverters) followed second with normal diverters **702D** (or a higher percentage of normal diverters). Still further, as shown below in a step **1116** when additional diverters are introduced, those may have a greater percentage of normal diverters **702D** of the total diverters then introduced, as compared to the earlier introduction, in step **1104**, of a higher percentage of smart diverters **704SD** introduced in step **1104**. In any event, optimally, monitoring every perforation, and the diverter (smart or normal) seating of each such perforation, may contribute to detecting, determining, and optimizing effective well stimulation.

Next, in step **1108**, well fluid pressure (and possibly rate) is increased, which can occur after one or more of the step **1106** diverters have been detected as seated. The pressure increase can be linear or in some other manner, including through the use of pressure pulsing as described in later figures, and the amount (and technique) of the increase may or may not be indicated at least in part by information provided by smart diverters **704SD** already downhole in the wellbore **106**. In any event, the pressure increases until breakdown occurs, that is, where the rock formation **100** proximate some (or all) of the step **1102** perforations begins to break or become more permeable, as will be detected by a change in pressure. The pressure at which breakdown occurs is referred to in the art as breakdown pressure, and in step **1110**, that pressure is measured and stored by one or more of the downhole smart diverters **704SD**. In an example embodiment, the step **1108** fluid pressure increase is applied before all of the **S1** smart diverters **704SD** seat into respective perforations, and as that pressure increases, it will reach the breakdown pressure, which can be detected by both not-yet-seated smart diverters **704SD** near the point of breakdown, or nearby seated smart diverters **704SD**, as each is operable to detect (and store) dynamic fluid pressure, which will change at least in the portions of fluid in proximity with the perforation adjacent the formation that is breaking down. For sake of reference, the initial breakdown pressure is referred to herein as **IBP1**. The **IBP1** value measured by one or more smart diverters **704SD** can be stored in the respective diverter memory, at least until the diverter is able to transmit the information, which can be while the diverter is in the wellbore **106**, or later once (or if) the diverter is retrieved from the wellbore **106**.

Next, in step **1112**, well fluid pressure (and possibly rate) is further increased, beyond the step **1108** **IBP1** pressure, and again the pressure increase can be linear, involve pressure pulsing, and the amount (and technique) of the increase may or may not be indicated at least in part by information provided by smart diverters **704SD** already downhole in the wellbore **106**. As the pressure increases, it is expected that fracturing in the rock formation **110**, proximate one or more of the step **1102** perforations, will begin to further extend into the formation **110**. Accordingly, in step **1114**, the smart diverter(s) **704SD** take and store pressure measurements during the time of the step **1112** pressure increase. For example, each smart diverter **704SD** can be

programmed to take pressure at a rate according to the diverter's operational speed, storage capability, power requirements, and the like. The step 1114 pressure measurements can be evaluated by a computational system, which can include any one or more of the processing circuits in FIG. 10, again for example to detect changes in dynamic pressure that differ from the intended increasing fluid pressure from the step 1112, particularly with such changes proximate to unseated perforations, or also to include changes in the rock formation pressure (differential pressure) that may be measured by a seated smart diverter and that occur at a rate that differs from the increasing fluid flow pressure in the wellbore 106. Such a differing pressure rate change may signal the timing, and the corresponding pressure at such times, when fracturing extension beyond the initial breakdown occurs. These evaluations may be performed during the step 1114 or thereafter, to determine what is referred to herein as the extension of fractures pressure, referred to as EOFP1. Lastly, note that steps 1112 and 1114 can continue for additional extension of fracturing in the rock formation, and to record additional corresponding pressures. For example, having obtained the initial IBP1 and the subsequent extended EOFP1, the wellbore 106 fluid pressure may be increased further until extension propagation of the fractures is detected (again through further pressure changes), and the pressure at which that extension occurs also may be detected and stored by the smart diverter (s) 704SD, for example as a parameter referred to as a propagating of fracture pressure POFP1.

Next, a step 1116 introduces a second set of an integer number S2 of diverters into the wellbore 106, where one or more of the S2 diverters is a smart diverter 704SD (or 706SD, as shown in FIG. 7B). The S2 diverters may be introduced at the well head 102, either manually, or through a partially or fully automated apparatus, and are carried downhole by the pumped fluid. The S2 diverters, and particularly the smart diverters 704SD in that set, are also introduced for their pressure-detecting and reporting functionality, but also to seat in perforations through which sufficient fracturing of the formation 110 occurred during the prior steps, so as to later provide proper oil/gas production once the well completion is finished. At this point, those perforations, through which sufficient fracturing has occurred, may be considered as the primary perforations (or perforation clusters) out of the entire P1 perforations formed in step 1102 in the current stage, while the step 1116 and subsequent steps are directed to remaining (secondary) perforations in those P1 perforations, which have yet to be sufficiently stimulated, so as to sufficiently fracture the formation through those additional secondary perforations. Accordingly, in the step 1116, generally the number S2 is chosen so that S1+S2 is less than or equal to P1, so that as the additional S2 diverters seat within respective perforations, those seated diverters divert well fluid flow and pressure to the remaining, secondary ones of the P1 perforations that remain unseated by a diverter, so as to permit additional fracturing through those secondary perforations.

Next, a step 1118 generally repeats steps 1106 through 1114, but now with respect to the smart diverters 704SD of the step 1116 S2 diverters. For example, in the repetition of step 1106, the pressure detected by each of those smart diverters, in the S2 diverters, may be stored, and potentially read, to determine when (or if) each of the diverters seats into a remaining unseated (secondary) perforation. Thereafter, in a repeat of steps 1108 and 1110, the well fluid pressure is increased until initial breakdown occurs through one or more secondary perforations, and the initial break-

down pressure at which that occurs, hereafter referred to as IBP2, is detected and stored by the smart diverter(s). Similarly, next the steps 1112 and 1114 are repeated for the secondary perforations and corresponding smart diverters, whereby well fluid pressure is increased further, and the extension of fracture pressure, EOFP2, for one or more secondary perforations is measured and stored.

After the above steps are complete, different example embodiments may perform additional steps, either with 10 smart diverters detecting and storing (for transmission) additional pressures or in taking subsequent well completion acts in response to the measured and stored smart diverter data. For example, if the total number of step 1102 perforations P1 exceeds S1+S2, or if the smart diverter data stored 15 at this point indicates or suggests a number of the P1 perforations not yet seated by respective diverters, then another set of diverters (e.g., of number S3) may be introduced into the well bore 106, and the steps 1106 through 20 1116 may be repeated for those additional diverters. Once a sufficient number of diverters (e.g., S1+S2, or S1+S2+S3) have been introduced into the well bore 106, and when it is detected that a sufficient number of those have seated into 25 respective ones of the P1 perforations, then additional steps may be taken. For example, FIG. 11 illustrates a conditional step 1120, which evaluates a smart-diverter informed condition (or plural conditions) and directs the next well completion step based on the condition(s).

In the illustrated example, the step 1120 essentially evaluates the wellbore stage heterogeneity (lack of uniformity in 30 attributes) based on the differences between one or both of IBP1 compared to IBP2, or EOFP1 to EOFP2. Specifically, recall that IBP1 relates to the first set of well-introduced diverters and the possible primary perforations, while IBP2 relates to the second set of well-introduced diverters and the 35 possible secondary perforations. Accordingly, one possibility is that the primary perforations are proximate rock formation that breaks down easier than the secondary perforations, so that IBP1 should be less than IBP2, by at least some expected percentage. A similar observation can be 40 expected with respect to EOFP1 to EOFP2. The step 1120 therefore compares IBP1 to IBP2, and if within a percentage shown as X %, the method continues to step 1122, while if beyond the percentage X %, the method continues to step 1124. A similar comparison, either alone or in combination 45 with the IBP1 to IBP2 comparison, is made with respect to a comparison of EOFP1 to EOFP2 by a percent Y %, which also can direct the method to either step 1122 or step 1124.

Step 1122 is reached when IBD1 is within X % of IBD2 (or possibly if EOFP1 is within Y % of EOFP2), so if X is 50 relatively low, this means IBD1 and IBD2 are close (i.e., within the low X %) to the same value. In this case, this means the rock formation properties, for both the primary and secondary perforations, may be considered similar, that is, having a low heterogeneity as between the rock formations corresponding to those perforations. Accordingly, the step 1122 can include, or lead to, additional well completion actions consistent with low heterogeneity. For example, if not all perforations have been seated with diverters, low heterogeneity also might permit the introduction of additional diverters, while using the already-known IBP1 and EOFP1 values to fracture through the remaining, unseated perforations.

Step 1124 is reached when IBP1 is not within X % of 55 IBP2 (or possibly if EOFP1 is not within Y % of EOFP2). So, if X is relatively low, this means EOFP1 and EOFP2 are sufficiently different from one another. In this case, this means the rock formation properties, for both the primary

and secondary perforations, may be considered dissimilar, that is, having a higher heterogeneity as between the rock formations corresponding to those perforations. Accordingly, the step 1124 can include, or lead to, additional well completion actions consistent with higher heterogeneity. For example, higher heterogeneity may suggest the current stage be plugged at this point, and a new stage started as pressure application and measurements may need to be more uniquely tailored for the next stage, given its relatively likelihood of differing from the prior stage, based on higher heterogeneity.

Method 1100 is but one example of many methods that may be implemented using smart diverters to measure/detect and store/transmit downhole attributes, such as pressures (including static, differential, changes (e.g., IPB, EOFP, subsequent propagation of fracture pressure), spikes, etc.), timing, and/or acoustics, and then responding to the smart diverter attribute(s), and also to adapt well completion apparatus and methods to those attributes. For example, as smart diverters are being used during completion of a lateral well, the attributes of that well, or even attributes from prior laterals that were completed using smart diverters, may be analyzed for improving completion. For example, the attribute(s) provided from one or more smart diverters, and including whether the smart diverters are flowing, or seated, or seated in an already stimulated versus a still unstimulated (or insufficiently stimulated) perforation, can help identify open perforations, partially stimulated perforations, and other subsurface information. As another example, a pattern can be recognized in smart diverter provided attributes, either from repeated instances in a same lateral, or in other laterals (e.g., in the same geographic region), can represent a “signature” for the corresponding lateral, and may sufficiently match the signature of other laterals, so that completion operations used on earlier-completed laterals that resulted in improved completion, such as providing better completion efficiency, lower cost, faster completion, fewer lateral stages, or the like, can be used for subsequently-completed laterals that have a same or similar signature. Such smart-diverter attributes, including detected signatures and comparison to prior identified lateral signatures, may be implemented, for example, using the FIG. 10 system, whereby prior lateral signatures may be stored in either the system memory 1006 or in remotely-accessed storage, for example via the WAN or in the database 1014. In this regard, as a well lateral is being fracked, smart diverters are introduced into the well, the smart diverters measure/detect and store/transmit downhole attributes, and those attributes are compared to like attributes from prior-completed wells (or prior completed laterals in the same well). If the attribute(s) is sufficiently close to the attribute of a prior-completed well (or lateral), that is, if the signature of the presently-fracked well is sufficiently close to the signature of a prior-completed well (or lateral), then the completion steps used for the prior-completed well can be used for the presently-fracked well, or can at least serve as an initial baseline process, which can be modified further to either further improve completion, or as differences in the signature of the prior-completed well and the presently-fracked well are continuously uncovered using the ability of the smart diverters. In this way, completion design time and costs also can be reduced.

FIGS. 12A and 102 illustrate a pulsing fracing system 1200. As background, during the fracing phase to perforate the well, it has been proposed in the art to cycle the downhole pumping fluid engine(s) on and off to create variations in pumping pressure, seeking to more effectively

perforate the rock formation proximate and outside the well casing in desired locations (i.e., to enhance porosity and permeability). Such cycling, however, could create considerable cost and durability risks, and potentially increase safety concerns, in connection with the operation of such engines, and the associated high-pressure and flow-rate fluid connections to those engines. The system 1200 contemplates an improved alternative, as is described below, and without requiring the sudden turning on and off of the frac fluid pumping engine(s), to create pulsing that provided for periodic, including rapid and sharp, variation in the frac fluid flow rate (pressure spikes) thereby produce pressure pulses. Indeed, decades ago fracing was performed using explosives (e.g., nitroglycerine). Such approaches were effective in creating what was believed to be complex fractures in the rock formation in the areas of the wellbore where the explosion occurred, but of course use of explosives was very dangerous, potentially toxic, and subject to limited control. Eventually such explosives were replaced with more controllable techniques, involving very large pressures and flow rates, as is common in modern fracing. However, example embodiments are provided below and that include pulsing apparatus in various alternative forms, each providing pressure changes in short duration spikes (e.g., 100,000 psi or greater, for example several hundreds of thousands, for example up to 500,000—or greater if achievable by equipment and related apparatus). Such pressure spikes may match, if not exceed, the fracing pressures created previously by explosives, yet in a safer and more controlled environment, also thereby achieving highly complex fractured rock systems (“HCFS”) and flow paths for subsequent oil and gas recovery. Still further, example embodiments provide the pulsing in repeated fashion, whereby it is expected that ongoing pulsing can have a cumulative effect to further enhance the fracing effect of rock formations. For example, pulsing essentially pulverizes/shatters the surrounding rock formation by the ongoing rhythmic heartbeat-like operation of ongoing and periodic high pressure pulses, thereby opening more fracture and channels that allow more oil to flow through the rock to the wellbore 106. Also contemplated is that pulsed spikes may be achieved while the frac fluid pumping engine(s) continue to provide a constant (or near constant) fluid pressure to the system 1200, whereby such pressure is augmented with additional apparatus, as may be implemented in a bypass system, as further described below.

The system 1200 includes various apparatus, which in one example embodiment, may be housed in a unitary and moveable structure (e.g., with a cabinet or other frame, and wheels). In this manner, the system 1200 may be affixed to an existing frac pump fluid system and, as will be detailed, can periodically bypass the standard frack fluid flow from pump engine(s) to the wellbore, without otherwise changing standard fracing process. Note that system 1200, as a bypass coupling, may be temporarily connected to the regular pump engine(s) or may be left connected on a longer term basis, so as to provide intermittent or continual pulsing over a long duration, such as full-time during the fracing stage of the well. In more detail, the system 1200 includes a bypass manifold 1202, for coupling to the existing frac fluid piping 1203. As a bypass connection, therefore, either the existing frac fluid piping 1203 provides an outlet 1203OUT by which normal fluid flow continues to the wellbore (not shown) or, alternatively, the system 1200 may be coupled by the bypass manifold 1202 to the piping 1203 and, with outlet 1203OUT closed, then the flow continues to the system 1200, and the system 1200 may be enabled/operated intermittently to

provide sharp pressure pulses in downhole fracing pressure, when desired. Thus, the system 1200 is intended to periodically bypass the standard frac fluid system, so that when system 1200 is operating and frac fluid flows through it, it will provide sharp pulse transitions in the fluid pressure flow, whereas when the bypass is not operated, the frac fluid may flow directly from the fracing engine(s) to the wellbore, the latter according to techniques known in the art. Accordingly, the manifold 1202 includes sufficient couplings, connections, and the like so as to couple to the fluid piping that receives pressurized frac fluid from a frac fluid engine (not shown). Frack fluid flow thusly couples, at the frac pumping pressure P_f , to an inlet 1202IN of the manifold 1202 and, when valve 1204 is open as described below, exits the manifold 1202 in pulsed pressures from an outlet 1202OUT. A reciprocating valve 1204 is enclosed within the manifold 1202, and may be implemented in various forms, so as to preclude a fluid flow path when the valve 1204 is in the closed Seal A position as shown in FIG. 12A, but alternatively to enable the fluid flow path when the valve 1204 is in the unsealed (open) position, as shown in FIG. 12B. The valve 1204 may, therefore, include a main member and various seals, guides, bearings, seating and the like, at either or both of its perimeter and ends. Further, as shown in FIG. 12A, the frac fluid flow is in a direction that, without an opposing force, maintains the valve 1204 in the closed Seal A position.

The system 1200 also includes apparatus for abruptly opening and closing the valve 1204, so as to periodically provide pressure fluid spikes or pulses from the outlet 1202OUT, with an open position of the valve 1204 illustrated in FIG. 12B. In the example embodiment as shown in both FIGS. 12A and 12B, such apparatus includes a flywheel 1206, which is intended to be an appropriately-sized and weighted/balanced wheel, having a generally and mostly circular outer perimeter. The flywheel 1206 is rotated by an engine or the like (not shown), at a speed to be determined based on considerations provided to, or by, one skilled in the art. In the illustrated example, the flywheel 1206 is shown to rotate clockwise. Along the generally-circular outer perimeter of the flywheel 1206, also included is one (or more than one) wedge 1208, which extends along an having an arc central angle θ , where the central angle θ also may be determined by one skilled in the art. The wedge 1208, for the duration of the central angle θ , is such that the radius of the flywheel 1204 continuously increases until a termination point 1208TP of the wedge 1208, at which point the radial increase is markedly disrupted and returned to the circular radius of the flywheel 1206. The system 1200 also includes a rod 1210. The rod 1210 has a bearing end 1210BE that bears against the outer perimeter of the flywheel 1206 and a distal end 1210DE that either contacts, or is connected or integral to, an end of the valve 1204.

FIG. 12B illustrates the operational impact of the system 1200. Specifically, as the flywheel 1206 rotates, the wedge 1208 correspondingly advances along the circular arc, for example to the position shown in FIG. 12B (the wedge position from FIG. 12A is shown in phantom, in FIG. 12B). As the bearing end 1210BE of the rod 1210 begins to incur the wedge 1208, the increasing radius provided by the wedge 1208 causes a linear displacement of the rod 1210, and correspondingly a linear displacement of the valve 1204. The linear displacement of the valve 1204 causes it to move to an unsealed/unseated position, as shown in FIG. 12B, thereby allowing frac fluid to flow through the manifold 1202. Further, with the pressure P_f having been stored behind the valve 1204 prior to the unseating movement (and

that pressure retaining the valve 1204 in a seated position), the abrupt opening of the valve 1204 causes a pressure spike, from no pressure to the sudden release of pressure, to be delivered through the manifold 1202 into the wellbore, via the outlet 1202OUT. Further, as the flywheel 1206 continues to rotate, eventually the bearing end 1210BE of the rod 1210 will encounter the termination point 1208TP of the wedge 1208. After the termination point 1208TP rotates beyond the bearing end 1210BE, the bearing end 1210BE will return to bear against the otherwise-circular perimeter of the flywheel 1206, with the rod 1210 again being urged into that position by the pressure P_f , pushing inwardly against the valve 1204, and the valve 1204 pushing inwardly against the rod 1210. At this point, therefore, the valve 1204 is returned to a sealed/seated position, akin to that shown in FIG. 12A.

FIG. 13A illustrates an alternative pulsing fracing system 1300, again with consideration to the prior discussion of perforating the well and proximate rock formation, without requiring the sudden turning on and off of the frac fluid pumping engine(s). The system 1300 includes various apparatus, also which in an example embodiment are housed in a unitary and moveable structure and that may be temporarily affixed to an existing frack pump fluid system to periodically bypass ordinary frac fluid flow to the wellbore. In more detail, the system 1300 includes a bypass manifold 1302, for coupling to the existing frac fluid piping, so that the system 1300 may enabled/operated intermittently to provide sharp downhole fracing pressure pulses. Thus, the system 1300 is intended to periodically bypass the standard frac fluid system, so that when system 1300 is operating and frac fluid flows through it, it will provide sharp pulse transitions in the fluid pressure flow, whereas when the bypass is not operated, the frac fluid may flow directly from the fracing engine(s) to the wellbore. Accordingly, the manifold 1302 includes sufficient couplings, connections, and the like so as to couple to the fluid piping that receives pressurized frac fluid from a frac fluid engine (not shown). Frack fluid flow thusly couples, at the frac pumping pressure P_f , to an inlet 1302IN of the manifold 1302 and may advance generally toward two different sets of apparatus: (i) a pressure bank 1304; or (ii) a rotating valve 1306, operated by a submersible variable high speed electric motor 1308. Each of these alternative paths is further discussed below.

Pressure bank 1304 is known in certain arts, as an apparatus in which fluid and gas are stored in a common tank (and separated from one another via a diaphragm 1310), sometimes for protective purposes. In the example embodiment, however, pressure bank 1304 is used in a dual cycle operation, a first pressure-storing cycle for storing frac fluid pressure and a second pressure-releasing cycle for releasing the frac fluid pressure. In this regard, a first portion 1304P1 of the volume of the bank 1304 includes a gas, such as nitrogen, enclosed by the diaphragm 1310. A second portion 1304P2 of volume of the bank 1104 receives frac fluid and its attendant pressure; hence, during the pressure-storing cycle, an increase in fluid to the portion 1304P2 displaces the diaphragm 1310 to compress the gas in the portion 1304P1 to essentially store pressure energy in bank 1304, and during the pressure-releasing cycle, a decreased pressure as described below permits the gas in the portion 1304P1 to expand so as to displace the diaphragm 1310 and release the stored pressure in the bank 1304 into the manifold 1302.

The rotating valve 1306 is shown in side view in FIG. 13A, and in frontal view that faces the motor 1308 in FIG. 13B. In the example embodiment, the valve 1306 has a circular outer perimeter and is connected by a shaft 1310 to

the motor 1308. Accordingly, as the motor 1308 rotates, the rotational force is applied via the shaft 1310 to the valve 1106, so that it also rotates, per the speed of the motor 1108. On the pressure-receiving side (or face) of the valve 1306, there are located pressure control apparatus, for example: (i) a plurality of fluid diverters 1312, which may be shaped protrusions or the like; and (ii) one or more apertures 1314. The pressure control apparatus are included so that at low (or no) speed rotation of the valve 1306, fluid pressure inside the manifold 1302 passes through the apertures 1314 to the outlet 1102OUT, whereas at high rotational speeds of the valve 1306, the diverters 1312 disturb fluid flow in a manner to limit or prohibit the passage of fluid through the apertures 1314. Given these two speed-responsive functions, note therefore that: (1) during the pressure-storing cycle of operation, the motor 1308 rotates the valve 1306 at a significantly high enough speed so that little or no pressure passes through the valve 1306, thereby applying back pressure inside the manifold 1302 and adding pressure into the bank 1304; and (2) during the pressure-releasing cycle of operation, the motor 1308 rotates the valve 1306 at a low (or no) speed, so that pressure of the fluid passes through the valve 1306, and at the same time reduces pressure within the manifold 1302, so that also at this time pressure stored in the bank 1304 is transferred into the interior of the manifold 1302, thereby pulsing the pressure applied at the outlet 1302OUT. Accordingly, with sufficient timing to the starting and stopping of the motor 1308, pressure spikes may be generated at the outlet 1302OUT. Further, the time elapsed between the first and second cycles will establish the duration and magnitude of the pressure pulse generated, and continuous rotation can provide a periodic and repeatable pulse train.

FIG. 14 illustrates a portion of another alternative pulsing fracturing system 1400, with various considerations akin to systems 1200 and 1300, as well as the prior art described above. The system 1400 includes a piston compression apparatus 1402 that couples pressure into a fluid manifold 1404. Apparatus 1402 includes a rotating assembly such as a crankshaft 1406 operated by a separate rotational force (e.g., motor or pump 1408), and a tie rod 1410 is pivotally connected to the crankshaft 1406, away from the rotating axis of the crankshaft 1206, so that rotation of the crankshaft 1406 translates to linear motion of a piston rod 1412 connected to the tie rod 1410. More specifically, the linear motion is also guided in that piston rod 1412 connects to a piston 1414, which is fitted within (e.g., by piston rings) a pressure cylinder 1416. Accordingly, as the motor 1408 rotates the crankshaft 1406, the piston 1414 reciprocates within the pressure cylinder 1416, as is known in certain arts. Where system 1400 differs considerably from such arts, however, is the example embodiment uses either a single piston, or plural pistons, operating so that all pistons move with a same offset on the crankshaft 1406 (or with the same timing on other respective crankshafts). Thus, instead of having a total N number of pistons, each timed to move 360/N out of degrees with another of the other respective pistons, in the system 1400, all pistons are timed to reach their maximum stroke at the same time. Thus, in contrast to prior art piston-based engines that seek offset firing for efficiency and dampening, the system 1400 configuration and timing causes an abrupt pressure surge as each piston reaches its concurrent maximum stroke. Further in the system 1400, each pressure cylinder communicates with a common fluid path. For example, FIG. 14 illustrates the manifold 1404, in fluid communication with the pressure cylinder 1416. Preferably, all other such pistons (not sepa-

rately shown) also fluidly communicate with the manifold 1404. Hence, frac fluid enters the manifold input 1404IN and is subject to the cumulative pressure of all pistons reaching maximum stroke at the same time. Hence, a cumulative pressure spike is introduced into the manifold 1404 at this occurrence. Further, the manifold 1404 includes a swaged (reduced diameter) section 1404SW, further increasing the pressure of the spike that is formed by the concurrent top-cylinder reach of the collective pistons in the system. The spiked output is then provided at the outlet 1404OUT of the manifold 1404, and as was with above embodiments, may then be introduced into the wellbore, for purposes of pulsed fracturing operations.

Various of the example embodiments include a manifold 15 for introducing items in the wellbore, such as diverters, pressure spikes, and the like. In connection with any of such manifolds, example embodiments contemplate adapting the manifold to introduction of such items, and also retrieving data via or through the manifold in connection with pressure 20 measurements made down the wellbore. Pressures are remarkably obtained, therefore, including pressure at: (i) formation break down, when the combined surface pump pressure plus the hydrostatic frac fluid column load (less the fluid column friction) exceeds the strength of the rock 25 formation being fracked; (ii) rock fracture initiation or rock fracture extension; and (iii) the time a diverter seats on a perforation. Example embodiments then process such pressures, using appropriate computational systems such as a computer station proximate the top of the wellbore, for 30 example included in the equipment 105. Such a computer station may operate alone, or in conjunction with other computer or data systems, including remote processing, as may be achieved via networking with other devices (e.g., mobile devices and networks, including cellular and the 35 Internet, as examples). With such pressures and other information, including that regarding specific location of pressure within the well, adjustments may be made to timing to complete one stage and start another, and possibly eliminating numerous stages in the fracturing process. Such elimination 40 can have massive impact on fracturing timing, the process, and the industry as a whole.

Given the preceding, while the inventive scope has been demonstrated by certain example embodiments, various alternatives exist. The foregoing description is of exemplary and example embodiments. The inventive scope, as defined by the appended claims, is not limited to the described embodiments. Alterations and modifications to the disclosed embodiments may be made without departing from the inventive scope. The meaning of the terms used in this specification are, unless expressly stated otherwise, intended to have ordinary and customary meaning and are not intended to be limited to the details of the illustrated or described structures or embodiments. Some embodiments include manners of detecting pressure and other measures at vast distances into the wellbore. Other embodiments include manners of creating HCFS, through pulsing of the frac fluid, preferably without interrupting the operation of the fluid pressurizing engines. Indeed, combining these embodiments may allow for more efficient fracturing, versus contemporary approaches. For example, a same or greater level of fracturing may be achieved, as compared to contemporary approaches, potentially in less time, with fewer human resources, fewer stages, and/or with reduced regular pressure (albeit periodically spiked), all of which also can lead to lower cost production. Further, one skilled in the art will appreciate that the preceding teachings are further subject to various modifications, substitutions, or alterations, without

departing from that inventive scope. Thus, the inventive scope is demonstrated by the teachings herein and is further guided by the exemplary but non-exhaustive claims.

What is claimed is:

1. A method of oil or gas production, comprising:
forming a wellbore in a rock formation, the wellbore
including a lateral portion;
introducing a plurality of perforation diverters into the wellbore, wherein each perforation diverter in the plurality of diverters includes circuitry for determining a pressure detectable by the perforation diverter; and
with each diverter in the plurality of perforation diverters, measuring a respective pressure detectable by the perforation diverter and within the lateral portion when the perforation diverter is seated in a perforation in the wellbore.
2. The method of claim 1 wherein the measuring step occurs by a first perforation diverter while seated in a first perforation and by a second perforation diverter while seated in a second perforation at a same time the first perforation diverter is seated in the first perforation.
3. The method of claim 1 and further including forming a plurality of perforations in the lateral portion, each perforation in the plurality of perforations fluid coupling the lateral portion to the rock formation.
4. The method of claim 3 wherein at least some of the plurality of perforations in the lateral portion are formed according to a timing responsive to a pressure determined by at least one perforation diverter.
5. The method of claim 1 wherein the circuitry for determining a pressure proximate the perforation diverter comprises circuitry for determining dynamic pressure.
6. The diverter of claim 1 wherein the circuitry for determining a pressure detectable by the perforation diverter comprises circuitry for determining differential pressure.
7. The method of claim 1 wherein the circuitry for determining a pressure detectable by the perforation diverter comprises circuitry for determining a first pressure and a second pressure.
8. The method of claim 7 and further comprising operating a processor to determine a rock formation breakdown pressure in response to a change between the first pressure and the second pressure.
9. The method of claim 1 and further comprising operating a selected perforation diverter in the plurality of diverters to communicate a pressure determined by the selected perforation diverter to an apparatus external from the selected perforation diverter.
10. The method of claim 1 and further including determining a location, inside the wellbore, of each perforation diverter in the plurality of perforation diverters.
11. The method of claim 10 and further including determining the location in response to positioning determining circuitry in each perforation diverter in the plurality of perforation diverters.
12. The method of claim 11 and further including determining the location in response to at least one material in the

wellbore, wherein the at least material is detectable by the positioning determining circuitry.

13. The method of claim 12 wherein the at least one material includes metal as a waveguide in the wellbore.
14. The method of claim 12 wherein the at least one material includes a magnetized material disposed at selected locations of the wellbore.
15. The method of claim 1 and further including determining a number of total frac stages of the wellbore in response, at least in part, to pressure determined by the plurality of perforation diverters.
16. The method of claim 1 and further including determining when each perforation diverter in the plurality of perforation diverters seats into a respective one of a plurality of perforations in the wellbore, in response to pressure determined by at least one or more of the plurality of perforation diverters.
17. The method of claim 16 and further including forming the plurality of perforations, wherein the step of determining determines when all perforations in the plurality of perforations are seated by a respective diverter.
18. The method of claim 1 wherein the introducing step comprises a first introducing step and the plurality of perforation diverters comprises a first plurality, and further including a second introducing step of introducing a second plurality of perforation diverters into the wellbore, wherein each perforation diverter in the second plurality of diverters does not include circuitry for determining a pressure.
19. A method of oil or gas production, comprising:
forming a wellbore in a rock formation, the wellbore
including a lateral portion;
introducing a plurality of perforation diverters into the wellbore, wherein each perforation diverter in the plurality of diverters includes circuitry for determining a pressure detectable by the perforation diverter; and
with each diverter in the plurality of perforation diverters, measuring a respective pressure detectable by the perforation diverter and within the lateral portion; and
further including determining a timing and amount of fluid pressure introduced into the wellbore in response, at least in part, to pressure determined by the plurality of perforation diverters.
20. A method of oil or gas production, comprising:
forming a wellbore in a rock formation, the wellbore
including a lateral portion;
introducing a plurality of perforation diverters into the wellbore, wherein each perforation diverter in the plurality of diverters includes circuitry for determining a pressure detectable by the perforation diverter;
with each diverter in the plurality of perforation diverters, measuring a respective pressure detectable by the perforation diverter and within the lateral portion; and
further including determining a timing and amount of fluid pressure pulsing introduced into the wellbore in response, at least in part, to pressure determined by the plurality of perforation diverters, the fluid pressure pulsing at 100,000 psi or greater.
